Patented Dec. 14, 1915.

UNITED STATES PATENT OFFICE.

HENRY B. HOVLAND, OF DULUTH, MINNESOTA.

APPARATUS FOR TREATING ORES AND OTHER MATERIALS.

1,164,189.

Specification of Letters Patent. Patented Dec. 14, 1915.

Application filed June 17, 1915. Serial No. 34,591.

To all whom it may concern:

Be it known that I, HENRY B. HOVLAND, a citizen of the United States, residing at Duluth, county of St. Louis, and State of Minnesota, have invented certain new and useful Improvements in Apparatus for Treating Ores and other Materials; and I do hereby declare the following to be a full, clear, and exact description of the invention, such as will enable others skilled in the art to which it appertains to make and use the same.

The present invention relates to apparatus for treating ores and other materials, and has for its object to provide an apparatus which is commercially adapted for sulfating ore pulp, then sulfidizing the same and subsequently floating off the sulfids in the manner hereinafter described.

The present application is directed specifically to a commercial type of apparatus, one form of which is disclosed in my co-pending application, Serial No. 31,898, filed June 3, 1915, in addition to a modified form of the apparatus involving the same principles of operation, but designed especially for laboratory use. In said application, both forms of the apparatus are claimed broadly and the laboratory apparatus is claimed specifically. In the present application, the commercial form of the apparatus is claimed specifically.

I have found in practice that in sulfating materials, if the reacting fluid constituents, such as available sulfur and available oxygen under superatmospheric pressure, are brought into the presence of the material to be sulfated, the superatmospheric pressure greatly promotes the reaction. The present application contemplates a commercial apparatus for permitting such a process to be carried on continuously and on a relatively large scale.

The invention further contemplates a combination of ore treating units in which the ore may be successively treated, so that the comminuted ore introduced to the machine will be discharged from the last unit in the form of sulfids which are floated off and the residual gangue and liquor which are drained off in the manner hereinafter described.

The invention is illustrated in the accompanying drawing, in which:—

Figure 1 is a vertical section, partly in ele-

vation, of the apparatus illustrated more or less diagrammatically; Fig. 2 is a transverse vertical section taken on the line 2—2 of Fig. 1; Fig. 3 is a broken perspective view of a portion of the flotation unit; and Fig. 4 is a horizontal section taken on the line 4—4 of Fig. 2.

In the form of the apparatus illustrated in the drawing, four main units are assembled, the first unit being denoted generally by the reference character A, and which comprises a plurality of ore bins or ore locks for feeding the ore to the sulfating unit, indicated at B. From the sulfating unit B, the material under treatment passes to the receiving bins or ore locks C from which it is discharged into a sulfidizing unit D. From the sulfidizing unit, the material passes into the flotation unit denoted generally by the reference character E.

The sulfating unit B comprises an outer casing 1 capable of withstanding superatmospheric internal pressures, and preferably has a protective lining of wood or other suitable material, indicated at 2. Certain parts of the lining 2 which are spaced from the outer casing 1 are provided with openings 3 to equalize the pressure on both sides of the lining.

Positioned within the casing 1 are a plurality of containers 4, through which the ore pulp successively passes in its travel through the sulfating unit. The containers 4 may be constructed in any suitable manner, but preferably they are formed by positioning partitions 5 in an inclosed casing 6. The partitions 5 are provided at their lower portions with openings 7 and at their upper portions with openings 8. It is, therefore, obvious that material under treatment may pass from one container to the next through the lower openings and the gaseous fluids above the surface of the liquid in the containers may pass from one container to the next through the upper openings. It is also obvious that before either the material can be discharged from the containers or the gaseous fluids permitted to escape into the casing 1, all of the container must be traversed by the gaseous fluids and the material under treatment. After the gaseous fluids have so passed through all of the containers, they are discharged through the opening 9 into the outer casing 1 and then through the

bleeder valve 10, in the manner hereinafter described.

Positioned in each of the containers 4 is a rotary agitator 11. As the agitator constitutes the subject-matter of one of my co-pending applications, it is sufficient for the present purposes to know that the agitator heads are carried by hollow stems 12 and are capable of delivering through radial passages provided in their heads, gaseous fluid which is drawn down through the interior of the hollow stems 12. The tops of the stems are closed, but openings 13 are provided in the stems just above the level of the material in the containers through which the gaseous fluid present in each container above the surface of the liquid may be drawn down through the hollow stem of the agitator and delivered by the agitator head to the material through which the gaseous fluids rise in the form of numerous finely divided bubbles. The agitators are intergeared by means of the friction wheels 14, all of which may be driven by means of a driving friction wheel 15 carried by a stub shaft 16, which may be driven from a pulley 17 through a knuckle joint 18. The pulley 17 is preferably positioned outside of the casing 1 and the friction wheels 14, for driving the agitators, are preferably positioned just above the top of the casing 6.

The comminuted ore or other material to be treated is fed into the containers from either one of the ore locks A through the intermediary of a pipe 19. In the present instance, two feed ore locks are shown, one being indicated at 1^a and the other at 2^a. The ore locks are provided with inlets controlled by the gate valves 3^a and 4^a, respectively, and outlets controlled by the gate valves 5^a and 6^a, respectively. The comminuted ore may be fed to either of the lock bins from a bin 7^a by means of the conveyer 8^a. A similar compound conveyer 9^a positioned below the outlets of the ore locks feeds the ore from either the ore lock 1^a or 2^a into the pipe 19. The interior of the bins 1^a and 2^a may be placed in communication with the interior of the casing 1 by means of the connecting pipes 10^a and 11^a, respectively. These pipes are controlled by means of the three-way valves 12^a and 13^a, respectively, by means of which the interior of the bins 1^a and 2^a may be placed in communication with the atmosphere or else in communication with the interior of the casing 1.

Water is introduced into the apparatus preferably through a pipe 20 controlled by valve 21 and communicating with the pipe 19, through which the dry ore passes. The water introduced through the pipe 20 mixes with the dry ore and the ore pulp passes into the end container 4. The fluid reacting constituents above referred to, which may be a mixture of substances containing

available sulfur and available oxygen, such as sulfurous acid and air or smelter smoke, are admitted to the containers through a pipe 22 controlled by a valve 23. The sulfate liquor passes from the bottom of the last container 4 through a pipe section 24 and rises in the pipe 25, while the sands drained from the last container pass downwardly in the pipe 25. The sulfate liquor rises through the pipe 25 into a receptacle 26, and then overflows into a pipe 27 leading downwardly toward the ore locks C. The receptacle 26, therefore, serves to maintain a constant level of the liquid in the containers.

After sulfating, it may sometimes be desirable to add certain materials, such as ferric sulfate, to the sulfated substance to place the same in proper condition for sulfidizing in the unit D, hereinafter described. The ferric sulfate serves to neutralize the free sulfurous acid and also serves to react for sulfidizing purposes with the calcium sulfid subsequently added in the unit D. For this purpose, a bin 28 is provided having an inlet controlled by a gate valve 29 and an outlet controlled by a gate valve 30. Material may be conveyed from the bin 28 into the receptacle 26 by means of a conveyer 31. A connecting pipe 32 places the interior of the casing 1 in communication with the interior of the bin 28 when the three-way valve 33 is in one position, thus equalizing the pressure in the bin and casing, and places the interior of the bin 28 in communication with the atmosphere when in another position.

Samples may be withdrawn from the sulfating unit for testing through a pipe 34 passing downwardly into the last container and ending in the vicinity of the discharge pipe 24. This pipe may be provided with a controlling valve 35, which, when opened, will permit the pressure in the casing to force some of the material out into a suitable receptacle for testing.

The lower end of the pipe 25 communicates with a cross conduit 1^c in which operates a conveyer 2^c for conveying the sands into either the receiving lock bin 3^c or 4^c. A gate valve 5^c controls communication between the pipe 25 and the cross conduit 1^c and may be left in such a position that the sands will pass into the cross conduit 1^c only with sufficient rapidity to cause an accumulation of the sand in the lower part of the pipe 25, thereby causing the sulfate liquor to rise in the pipe 25 and overflow into the pipe 27, as above described. The lower end of the pipe 27, through which the sulfate liquor descends, is provided with two branches 6^c and 7^c controlled by the gate valves 8^c and 9^c, respectively. The sulfate liquor passes through either the branch 6^c and 7^c depending upon which gate valve 8^c and 9^c is opened, and then mixes with the

sands at either end of the cross conduit 1^e, and then the mixture is delivered to either the lock bin 3^e or 4^e depending upon which gate valve 10^e or 11^e is open.

The pressure may be equalized in the casing 1 and the ore lock 3^e by means of a connecting pipe 12^e controlled by a valve 13^e. Likewise, the pressure in the ore lock 4^e may be equalized with the pressure in the casing 1 by means of the connecting pipe 14^e controlled by a valve 15^e. A branch pipe 16^e connects the pipe 12^e with the space under the bin floor 22^e, thereby equalizing the pressure above and below the bin floor. This branch pipe 16^e is controlled by a three-way valve 17^e which may serve to place the pipe 12^e in communication with the space below the bin floor 22^e or may serve to place the interior of the bin 3^e in communication with the atmosphere when 13^e is closed. A branch pipe 18^e and three-way valve 19^e associated with the ore lock or bin 4^e serve the same purpose with respect to the ore lock 4^e, as the branch pipe 16^e and three-way valve 17^e just described.

The outlets of the ore locks 3^e and 4^e are controlled by the gate valves 20^e and 21^e. The material is fed from either the ore lock 3^e or 4^e into the sulfidizing unit D, which may comprise a tank or container 1^d to which the sulfidizing agent may be admitted from a bin 2^d by means of a conveyer 3^d. Passing downwardly into the container 1^d is a hollow tube 4^d which terminates at a point just above the bottom of the container 1^d. The material in the container 1^d is drawn up through the pipe 4^d by suction produced by means of the rotary element 5^d comprising two spaced plates having radial passages 6^d positioned therebetween. This rotary element may be driven by means of a pulley 7^d connected therewith, and when so driven will draw material up through the pipe 4^d, and then deliver the material radially in all directions in the container 1^d. For this purpose, the interior of the pipe 4^d is in communication with the space between the plates of the rotary element 6^d. Some of the sands passing upwardly through the pipe 4^d may tend to clog the same and in order to prevent this, a conveyer 8^d is preferably positioned inside of the pipe 4^d and is rotated by means of a pulley 9^d. The outlet of the sulfidizing container 1^d is controlled by means of a gate valve 10^d. When this valve is opened, the material then passes into the flotation unit E.

The flotation unit may comprise a plurality of containers 1^e separated by means of the partitions 2^e having openings 3^e in their lower portion to permit passage of the material from one container to the next. Each container has positioned therein a tapering neck portion 4^e above the opening in which is provided a rotary skimmer 5^e. Each con-

tainer has positioned therein an agitator 11 similar to that used in the sulfating unit B and the rotary skimmers 5 may be secured directly to the stems of the agitators. As will be noted from Fig. 4, the skimmers may comprise a wheel-like structure having radial spokes 6^e for blowing off the froth and for throwing the same off by actual contact therewith. The stems of the agitators pass upwardly through the partitions 7^e and 8^e (Figs. 2 and 3) and the agitator stems are interconnected just above the lower partition 7^e. As best shown in Figs. 2 and 3, the upper portions of the series of containers are inclosed by means of a closure-like portion 9^e of the casing comprising the top 9^e and the sides 10^e. The top 9^e rests upon the transverse supports 11^e (Fig. 1) and the sides 10^e are bolted against the partitions 2^e by means of the bolts 12^e. As shown in Figs. 2 and 3, there is an opening left at each side of the casing between the lower edges of the upper side walls 10^e and the upper edges of the lower side walls 13^e. These openings are indicated at 14^e and are for the purpose of permitting the froth skimmed from the tops of the containers to pass into the troughs 15^e, one of which is provided at each side of the casing and runs longitudinally thereof. It will be noted that the partitions 7^e and 8^e are of less width than the top portion of the casing, and, therefore, instead of fluid which, in the present instance, is air, being drawn down through openings in the sides of the agitator stems, it is drawn down through the tops of the agitator stems which are left open for the purpose. Lateral closures 16^e hinged to the upper portion of the casing, as shown at 17^e, serve to inclose the troughs 15^e and confine the air, or any other gaseous fluid which may be used, in the casing, so that the agitators will circulate the same air over and over again through the material in the containers.

The material is introduced to the flotation unit E from the sulfidizing unit D through a conduit 17^e. In order to place the sulfids in condition for floating, it is necessary to add thereto a small quantity of oil or similar material, and this may be introduced from a receptacle 18^e through a valved outlet 19^e discharging into the conduit 17^e. A spitzkasten 20^e, disposed adjacent to the last container 1^e and in communication therewith at the lower portion of the last container, serves to maintain a constant level of the material in the containers. A valve 21^e provided at the lower portion of the spitzkasten permits the gangue and residual sands to be drained therefrom, and the liquid part of the pulp overflows into and is carried away by trough 22^e.

The operation of the apparatus as above described is as follows. Assuming that all of the valves are closed, the ore or other

material to be treated is thoroughly crushed and ground to pass an 80-mesh screen and is fed from the bin 7^a into either the ore lock 1^a or 2^a. Assuming that the material is fed first into the lock 1^a, the gate valve 3^a associated therewith is opened and the conveyer 8^a is rotated to feed the material into the lock bin 1^a. When the ore lock has been filled, the gate valve 3^a is closed and the valves 10^c, 5^c and 13^c, controlling communication between the sulfating unit and the ore lock 3^c, are opened and three-way valve 12^a is so turned as to place the feed ore lock 1^a in communication with the interior of the casing 1 of the sulfating unit. The valve 21 of the sulfating unit is then opened to admit water through the pipe 20 into the containers 4 until the proper level is reached, and thereafter the valve 21 is left open the proper amount to maintain a constant level of the liquid in the containers during the sulfating operation. The valve 23 is then opened to bring into the presence of the material in the containers, a mixture of sulfurous acid and air, or other reacting agent or agents, such as smelter fumes. These fluid constituents are admitted until the pressure in the casing reaches approximately 100 lbs. to the square inch, and thereafter the pipe 22 is connected to a source of sulfurous acid and air supply under a constant pressure of about 100 lbs. to the square inch. Due to the presence of the connecting pipes between the feed ore locks and the discharge ore locks, the same pressure obtains in all parts of the apparatus and therefore the passage of material from one part to the other takes place the same as if all the parts were positioned in one casing capable of maintaining the same pressure on all the parts.

The gate valve 5^a controlling the outlet from the ore lock 1^a is then opened and material is then gradually introduced by means of the conveyer 9^a through the pipe 19 in the containers 4. This feeding of the material is readily accomplished, since the pressure in the ore lock 1^a is the same as that in the containers. The agitators 11 are then set in operation and the fluid reacting constituents in the containers are drawn down through the openings 13 and the hollow stems of the agitators and delivered to the material in the containers by the agitator heads. The suction zone produced in the vicinity of each agitator head automatically draws the fluid constituents down into the liquid and circulates them through the liquid in the form of finely divided bubbles. The fluid is successively passed from one container to the next and in each container is circulated through the material, so that by the time the last container has been reached, a substantial amount of the available sulfur and available oxygen has been

used from the sulfurous acid and air. Fresh sulfurous acid and air, however, are constantly supplied through the pipe 22 and the bleeder valve 10 may be partially opened to permit a constant circulation of the sulfurous acid and air through the containers, and then into the casing through the opening 9, and thence through the bleeder valve 10. The sulfurous acid and air are supplied under constant pressure and the valve 10 is left open, or partially open, determined by the amount of reacting gaseous constituents required by the material under treatment. It is obvious that the fluid reacting constituents need not be admitted at the same end of the apparatus as the material, as it may be desirable, in some instances, to pass the fluid constituents through the containers in the opposite direction to the passage of the material. Furthermore, if desired, the fluid reacting constituents may be admitted to any one of the containers and caused to flow in opposite directions through the containers at either side of their place of admission.

By the time the material reaches the last container, it is sulfated and the sulfate liquor passes through the pipes 25 and 27 into the receiving lock bin 3^c, the valve 8^c having been previously opened for this purpose. On its way to the lock bin 3^c, however, the sulfate liquor has been supplied with material from the bin 28 to place it in proper condition for sulfidizing, it being understood that the valve 33 is first so turned as to equalize the pressure in the bin 28 and the casing 1, so as to permit feeding of material from the bin into the receptacle 26, and that the valve 30 controlling the outlet of the bin is first opened. The bin 28 may be refilled by closing the gate valve 30 and reducing the pressure in the bin through the three-way valve 33.

The gangue and sulfate liquor discharged from the sulfating unit pass through the gate valve 10^c into the receiving ore lock 3^c in which the pressure is the same as in the casing 1. The process is continued until the receiving ore lock 3^c is filled, at which time, it will be assumed that the material to be treated has been completely discharged from the ore lock 1^a. During the discharge of the material from the ore lock 1^a, however, the ore lock 2^a has been filled by reversing the direction of rotation of the conveyer 8^a. The process may, therefore, be continued by equalizing the pressure in the ore lock 2^a and the casing 1 through the pipe 11^a, and then feeding material from the ore lock 2^a into the sulfating unit B. The pressure in the ore lock 1^a may then be reduced by turning the three-way valve 12^a to place the interior of the ore lock in communication with the atmosphere, before which, however, the gate valve 5^a must be closed. The ore lock may then be refilled while the material is

being discharged from the ore lock 2^a. When the material is exhausted from the ore lock 2^a, it is obvious that this ore lock may be refilled in the same manner. As the receiving ore lock 3^c is now full, the valves 10^c, 13^c and 8^c are closed and the corresponding valves for the other lock, to wit, valves 9^c, 11^c and 15^c are opened to permit feeding of the material into the receiving ore lock 4^c. The three-way valve 17^c associated with the lock bin 3^c is then turned to place the interior of the lock bin in communication with the atmosphere, thereby reducing the pressure. After the gate valve 20^c is opened, the material may be fed from the ore lock 3^c into the sulfidizing unit D. When the ore lock 4^c is full, the pressure in this ore lock may be reduced by means of the three-way valve 19^c after valves 11^c and 15^c are closed, and the material then fed from the ore lock 4^c into the sulfidizing unit, during which time, the ore lock 3^c may be refilled.

In the sulfidizing unit, the material has mixed therewith the sulfidizing agent and is circulated through the pipe 4^a and thrown outwardly by means of the rotary element 6^a to thoroughly mix the materials and produce a better sulfidizing action. The sulfidized material is discharged through the gate valve 10^a into the flotation unit in which the air or other fluid circulated through the material produced numerous finely divided bubbles which rise through the pulp and carry with them the oil-coated sulfidized metal. This produces an accumulation of froth at the top of each container which is skinned off by the skimmers 5^a and thrown against the walls of the casing. The froth then drains off into the troughs 15^a and may be conducted to any suitable place. The liquid part of the pulp having been deprived of copper or other metal in the flotation unit, flows over the edge of the spitzkasten into trough 22^a and is drained off and the gangue may be withdrawn from the bottom of the spitzkasten through the valve 21. It will be noted that a body of air is confined in the flotation unit and is used over and over again in being drawn down 45 through the agitators and delivered to the material. This is for the purpose of restricting the supply of oxygen, for if too much oxygen is supplied, the copper in the precipitated copper sulfid has a tendency to form copper sulfate. Therefore, the less oxygen contained in the air, the better, since the main purpose of circulating the fluid through the material in the flotation unit is to produce bubbles for carrying the sulfidized metal upwardly to the surface.

From the foregoing description, it will be seen that although the sulfating is carried out under superatmospheric pressure, the use of the superatmospheric pressure does not hinder the feeding of the material to

the apparatus or discharge the material therefrom, due to the arrangement of the feeding and receiving ore locks. I do not wish to be limited, however, to the number of feeding and receiving ore locks shown, 70 since it may be desirable to vary the number employed.

The sulfating and flotation units in combination produce in effect a continuous series of containers through which the material successively passes, and in each of which an agitator is provided for maintaining a constant circulation of the gaseous fluid in the container through the material, the fluid being confined in the group of containers 75 and caused to pass through the material in all of the containers.

Obviously numerous modifications and changes may be made in the details of construction as above described, without departing from the spirit or scope of the invention, as defined in the accompanying claims.

What I claim is:

1. An apparatus for treating ores and other materials, comprising an inclosed casing adapted to inclose the material to be treated, an inclosed bin, said casing and bin adapted to withstand superatmospheric pressure, and means to permit passage of said material from the bin to the casing 90 while both are under the same superatmospheric pressure.

2. An apparatus for treating ores and other materials, comprising an inclosed casing adapted to inclose the material to be treated, an inclosed bin, said casing and bin adapted to withstand superatmospheric pressure, means to equalize the pressure in the bin and casing, and means to permit passage of said material from the bin to the 100 casing while both are under the same superatmospheric pressure.

3. An apparatus for treating ores and other materials under superatmospheric pressure, comprising an inclosed casing, an inclosed feed bin, and an inclosed receiving bin all connected by passages serving to establish and maintain equal internal pressures in the bins and casing, means for advancing the material under treatment from the feed bin to the casing, means for advancing the material from the casing to the receiving bin, and means for supplying and discharging fluid agents to and from the apparatus.

4. An apparatus for treating ores and other materials under superatmospheric pressure, comprising an inclosed casing, a plurality of inclosed feed bins, and a plurality of inclosed receiving bins, all connected by passages serving to establish and maintain equal internal pressure between the said casings and said bins, means for advancing material under treatment from the said feed bins to the said casing, means for 120 125 130

advancing the material from the casing to the receiving bins, and means for supplying and discharging fluid agents to and from the apparatus.

5. Apparatus for treating ores and other material, comprising a casing adapted to withstand superatmospheric internal pressures and adapted to inclose a body of the material to be treated, an inclosed bin for dis-

10 charging material into the interior of the casing, means to admit fluid under superatmospheric pressure to the casing, an inclosed bin for receiving material discharged from the casing, and means to equalize the 15 pressure in the casing and both of said bins.

6. Apparatus for treating ores and other material, comprising an inclosed casing adapted to withstand super-atmospheric internal pressures and to contain the material

20 to be treated, a plurality of inclosed bins for receiving material discharged from the casing, means to discharge material from the casing into any one of said bins, and means to equalize the pressure in any one of said 25 bins with the pressure in the casing.

7. Apparatus for treating ores and other material, comprising a casing adapted to withstand superatmospheric internal pressures and adapted to inclose a body of the

30 material to be treated, a plurality of inclosed bins for discharging material into the interior of the casing, means to feed material from any one of said bins to the casing, a plurality of receiving bins, means for feeding material from the casing into any one of 35 said receiving bins, and means to equalize the pressure in the casing and in any one or more of said bins.

8. Apparatus for treating ores and other materials, comprising a sulfating unit involving the use of a casing capable of withstanding superatmospheric internal pressures, means for holding material and feeding it into the interior of the casing, means 45 to receive material discharged from the casing, and means to equalize the pressure in the casing with that in the receiving and feeding means.

9. Apparatus for treating ores and other materials, comprising a casing adapted to withstand superatmospheric internal pressures and adapted to inclose a body of the material to be treated, an inclosed bin for discharging material into the interior of the 50 casing, said bin having a valve-controlled inlet and a valve-controlled outlet, and means for equalizing the pressure in the bin and casing.

10. Apparatus for treating ores and other material, comprising a casing adapted to withstand superatmospheric internal pressures and adapted to inclose a body of the material to be treated, a plurality of inclosed bins for feeding material into the interior of the 55 casing, each of said bins having

a valve-controlled inlet and a valve-controlled outlet, means for feeding material from any one of said bins to the casing, and means to equalize the pressure in the casing and in any one or more of said bins.

11. Apparatus for treating ores and other material, comprising a casing adapted to withstand superatmospheric internal pressures and adapted to inclose a body of the material to be treated, a plurality of inclosed bins for feeding material into the interior of the casing, each of said bins having a valve-controlled inlet and a valve-controlled outlet, means for feeding material from any one of said bins to the casing, 70 means to equalize the pressure in the casing and in any one or more of said bins, a plurality of inclosed receiving bins into which the material may be discharged from the casing, each of said receiving bins having a 75 valve-controlled inlet and a valve-controlled outlet, and means to equalize the pressure in the casing and any one or more of said receiving bins.

12. Apparatus for treating ores and other material, comprising a plurality of containers, means to introduce the material to be treated to the containers, means to permit passage of the material through the containers successively, a rotary agitator in 90 each of said containers, a casing inclosing said containers capable of withstanding relatively high internal pressures, and means to admit fluid-reacting constituents under superatmospheric pressure to the containers. 95

13. Apparatus for treating ores and other materials, comprising a casing adapted to withstand superatmospheric internal pressures, a plurality of containers positioned therein, means to admit the material to be treated to the containers, means to permit passage of the material through the containers successively, means to discharge the material from the containers after having passed successively therethrough, means to 100 pass fluid-reacting constituents successively through the containers, and an agitator positioned in each container, capable of maintaining a circulation of the fluid-reacting constituents through the material in the 105 container.

14. Apparatus for treating ores and other materials, comprising a casing adapted to withstand superatmospheric internal pressures, a plurality of containers inclosed by 110 said casing, means to cause the material to be treated to successively pass through all of said containers, means to cause fluid-reacting constituents under superatmospheric pressure to successively pass through all of 115 said containers, an agitator in each of said containers adapted to maintain a circulation of the fluid-reacting constituents in the container through the material therein, means to discharge the used reacting constituents 120

to the casing, and a bleeder valve associated with the casing, for the purpose described.

15. Apparatus for treating ores and other material, comprising a plurality of containers, means to cause the material to be treated to pass successively through said containers, means in addition to said first-named means for causing fluid to pass successively through the containers, and an agitator positioned 10 in each container adapted to maintain a circulation of the fluid in the container through the material therein.

16. Apparatus for treating ores and other materials, comprising a series of containers, 15 means for causing the material under treatment to pass successively through all of said containers, means to confine a body of fluid above the level of material in the containers, and an agitator in each container capable of 20 maintaining a circulation of the fluid through the interior of the agitator and the material in the container.

17. Apparatus for treating ores and other materials, comprising two series of containers, 25 means for causing the material under treatment to pass successively through all of said containers, means associated with each series of containers for confining a body of fluid above the level of the material in 30 the containers, and an agitator in each of

said containers capable of maintaining a circulation of the fluid through the interior of the agitator and the material in the container.

18. Apparatus for treating ores and other 35 material, comprising an inclosure adapted to withstand superatmospheric internal pressures and to contain a body of the material to be treated, an inclosed bin connected with the casing, and means to equalize the pressure 40 in the casing with that in the bin.

19. Apparatus for treating ores and other material, comprising an inclosure adapted to withstand superatmospheric internal pressures and to contain a body of the material 45 to be treated, a plurality of inclosed bins connected with the inclosure, and means to equalize the pressure in the inclosure with the pressure in any one of said bins.

20. Apparatus for treating ores and other 50 material, comprising a series of containers, means for causing the material under treatment to pass successively through said containers, and an agitator in each container adapted to maintain a circulation of gaseous 55 fluid through the interior of the agitator and the material in the container.

In testimony whereof I affix my signature.

HENRY B. HOVLAND.
